UNITED STATES PATENT OFFICE.

SAMUEL R. ULLMAN, OF WILKES-BARRE, PENNSYLVANIA.

CARTON.

1,112,042.

Specification of Letters Patent. Patented Sept. 29, 1914

Application filed July 20, 1912. Serial No. 710,715.

To all whom it may concern:

Be it known that I, SAMUEL R. ULLMAN, a citizen of the United States, residing at Wilkes-Barre, in the county of Luzerne and 5 State of Pennsylvania, have invented a new and useful Carton, of which the following is a specification.

This invention relates to cartons and aims primarily to provide a receptacle for receiving laundried goods, in which the laundried goods may be conveyed from the laundry to the patron without danger of the goods becoming soiled, although these cartons are also applicable to clothing, gents' furnishings and dry-goods, both by manufacturers and retailers, as receptacles for shirts, hand-kerchiefs, collars, shirt-waists, etc.

This invention also contemplates the production of a carton of the character indicated which shall be simple and inexpensive 20 in construction, which shall be capable of holding various quantities of goods, and which shall be convenient, hygienic and serviceable in its use.

With the foregoing general objects in view, the present invention resides essentially in a carton embodying a card-board back, and a paper front having bellows sides and bottom attached to the back and a closure flap bearing an adhesive substance to attach the flap to the back after the carton has been filled. Although the back and front have been described as being constructed of card-board and paper, respectively, it is understood that equivalent substances may be employed for either. The bellows sides and bottom permit the front and back to be distended relative to each other in order to accommodate the quantity of goods inserted 40 into the carton, and the closure flap bearing adhesive material may then be folded over the open end or mouth of the carton and secured to the back after the back and front have been sufficiently pressed together to retain the goods properly in position.

The invention has been illustrated in the accompanying drawings, wherein:—

Figure 1 is a perspective view of the carton. Fig. 2 is a plan view of the paper blank from which the front, sides, bottom and closure flaps are formed. Fig. 3 is a fragmental perspective view of the mouth or open end of the carton. Fig. 4 is a fragmental perspective view of the bottom of the 55 carton.

Referring in detail to the drawings, the

numeral 5 designates the card-board blank forming the back, which is shown as rectangular, and the numeral 6 designates the paper front which is also rectangular and 60 which corresponds in contour with the back 5. At this point it may be well to state that the front and back may be of any size, so as to accommodate the carton to various goods, the carton as illustrated being preferably 65 for shirts and like articles, whereas smaller cartons may be provided for collars, cuffs, and the like.

The blank forming the front 6 is provided with bellows sides 7 attached to the edges of 70 the front and a bellows bottom flap 9 attached to the lower end of the front, the sides 7 being provided with bellows bottom flaps 8 at their lower ends, which overlap each other. The bottom flap 9 overlies and 75 folds with the bottom flaps 8 and is secured thereto by adhesive material or otherwise. The sides 7, and bottom flaps 8 and 9, are each provided with only a single inwardly 80 folding plait, which is essential. The sides 7 are provided with the supplemental flaps 12 overlapping and secured to the edges of the back, the bottom flaps 8 are provided with the supplemental flaps 10 overlapping and secured to the lower end of the 85 back, and the bottom flap 9 is provided with the supplemental flap 11 overlapping and secured to the supplemental flaps 10. The sides 7 are also provided with bellows closure flaps 8' attached to their upper ends, 90 which are designed to overlap each other when folded over the mouth of the carton. The closure flaps 8' are provided with only single inwardly folding plaits, which is essential in connection with the single plaits 95 of the sides and bottom, the said flaps 8' being provided with supplemental flaps 10' adapted to overlap the corresponding edge of the back. The front 6 is also provided with a closure flap 9' attached to its upper 100 end bearing a strip of adhesive material 11' along its outer or free end. The closure flap 9' is longer than the bottom flap 9, the ends of the respective closure flaps 8' and 9' being flush, and the end of the bottom flap 8 being 105 inset from the ends of the flaps 8. The blank, as a whole, is substantially rectangular, with the exception of the slight recess provided by the bottom flap 9.

It will thus be observed that the carton is 110 constructed of two blanks, the stiff blank forming the back and the paper blank form-

ing the remainder of the carton, the carton therefore being of a semi-box-like and semi-bag-like structure. The said back provides suitable rigidity for holding the goods against abnormal crushing or bending action, and the bellows sides and bottom permits the front and back to be distended more or less to accommodate the particular quantity of goods it is desired to retain within the 10 carton. After the carton has been filled, the closure flaps 8' may be folded over the mouth of the carton so as to overlap each other, and after the front and back have been pressed sufficiently together, the closure flap 9' may 15 be swung over the closure flaps 8' and then secured to the back 5 by means of the adhesive substance 11'. Thus it will be noticed that the contents are enveloped in the carton so as to be protected against dust, moisture, air, light, and other foreign or extraneous matter, making it sanitary in every respect. It will also be apparent that the adhesive material 11' may be engaged to the back at any point along the length thereof 20 so as to accommodate the goods, and after the goods have once been inclosed within the carton, the same may be conveniently conveyed to the patron of the laundry or by the manufacturer, clothier, haberdasher, or dry-goods merchant to his patrons, without fear of the goods being soiled or otherwise injured.

From the foregoing, taken in connection with the drawings, it will be apparent that 35 the objects aimed at are attained in a satisfactory manner, and that the present carton provides a desirable one for the purposes to which it is designed. The particular grade of card-board and paper employed is of no 40 moment, and may be varied to suit the circumstances, and although the material employed has been denoted as card-board and paper in the appended claim, it is understood that equivalent materials are also inferred thereby.

Having thus described the invention, what is claimed as new is:—

A carton embodying a rigid rectangular blank forming a back, and a second blank comprising a rectangular front, sides attached to the edges of the front and each having a single inwardly folding plait, overlapping bottom flaps attached to the lower ends of the sides and each having a single inwardly folding plait, a bottom flap attached to the lower end of the front and having a single inwardly folding plait, the last mentioned bottom flap overlapping, folding with and being secured to the first mentioned bottom flaps, the sides having supplemental flaps overlapping and secured to the edges of the back, the first mentioned bottom flaps having supplemental flaps overlapping and secured to the lower end of the back, and the last mentioned bottom flap 65 having a supplemental flap overlapping and secured to the last mentioned supplemental flaps, closure flaps attached to the upper ends of the sides and each having a single inwardly folding plait, the closure flaps being designed to overlap each other, and having supplemental flaps to overlap each other and the upper end of the back, in order to limit the inward movement of the said closure flaps, and a closure flap attached to 70 the upper end of the front, the last mentioned closure flap being longer than the last mentioned bottom flap and having a strip of adhesive along its free end to permit the free end of the last mentioned closure flap 75 to be attached at various points over the back.

In testimony that I claim the foregoing as my own, I have hereto affixed my signature in the presence of two witnesses.

SAMUEL R. ULLMAN.
